CLAIM

The ornamental design of a book with flexible bag enclosure, as shown and described.

DESCRIPTION

FIG. 1 is a perspective of the invention of the book with flexible bag enclosure in a closed position;

FIG. 2 is a front view of the invention;

FIG. 3 is a first side view of the invention;

FIG. 4 is a rear view of the invention;

FIG. 5 is a second side view of the invention;

FIG. 6 is a top view of the invention;

FIG. 7 is a bottom view of the invention;

FIG. 8 is a second perspective of the invention with the book in an open position; and,

FIG. 9 is a front perspective view thereof in a closed position, the broken lines shown are for illustrative purposes only and form no part of the claimed design.
